WAD CUTTING, FORMING, AND PLACING
MACHINEDaniel D. Huyett, Wilmington, Del., assignor to
Atlas Powder Company, Wilmington, Del., a
corporation of Delaware

Application March 14, 1934, Serial No. 715,541

19 Claims. (Cl. 86—20)

This invention relates to wad cutting, forming and placing machines of the character of that shown in my copending application Serial No. 654,349, filed January 30, 1933; the present application being a continuation, in part, of the aforesaid application and being intended to cover certain refinements and improvements in the machine there illustrated.

The principles embodied in the machines of these applications are applicable in the general class of machines which form paper wads or caps and then insert the same into the open ends of tubular bodies.

An important use for a machine of this character is in the manufacture of the very popular form of cheap low explosive package marketed under the name "Blakstix". In the formation of this explosive package, simple paper tubes, open at both ends and formed of quite light-weight paper, are filled with black powder or like relatively low explosive; said powder being moist and more or less plastic when packed in said tubes. After the powder has been packed and levelled off in said tubes the packages are subjected to a drying operation under which the powder becomes quite hard. Wads or caps are then placed in each end of the paper tubes and the ends of the tubes are crimped over such wads to completely seal the package.

Prior to my invention of the machine described in my copending application it had been the practice to place these wads in the ends of the tubes or packages by hand. The machine disclosed in said copending application functioned to automatically cut off the necessary material for the wads from a strip of wad material, cup said material to form the wad, and then place the wad in position in the end of the package. Since the paper or other wad material employed is of quite light weight, it follows that it is easily deformed so that the ends of the packages do not present true circles.

One of the important features upon which the present application is based consists of the provision of improved means to facilitate the insertion of the wad even when the paper tube of the package is out of round.

A further object of the present invention is to provide means for venting the die to permit the ready escape of any fine powder particles which might otherwise be blown back into the mechanism and create an undesirable hazard.

The cutting off die in my copending application was moved positively in one direction by a cam and in the other direction by a spring or springs.

I have found it desirable in order to avoid any possibility of sticking of the parts to provide means for imparting a positive initial kick to this element in the direction of its spring actuated movement; the completion of the stroke being under the influence of the spring, and this feature also constitutes one of the improvements covered by the pending application.

In the accompanying drawings:

Figure 1 is a view, partly in plan and partly in horizontal section, of a mechanism constructed in accordance with the invention.

Figure 2 is a transverse sectional view of the die, hereinafter described.

Figure 3 is a side elevation of the structure of Fig. 1 and

Figure 4 is a fragmentary sectional view of the actuating mechanism of the wad placing means, hereinafter described, said section being a fragmentary section upon line 4—4 of Figure 1.

Figure 5 is an enlarged view showing the structure of the die throat and associated parts.

Like numerals designate corresponding parts in all the figures of the drawings.

I will first describe those portions of the mechanism which are like the corresponding portions in my former application and will then describe the additions and improvements which have been made therein.

The machine of my copending application discloses a pair of wad cutting, forming and placing mechanisms positioned upon opposite sides of a feed mechanism by which the open ended tubes are fed into alignment with said mechanisms; the wads being simultaneously thrust into the opposite ends of the tubes by said mechanisms.

The mechanism of the present application may be used and is primarily intended to be used in the same way, but since the mechanism is capable of functioning to apply a wad at one end of the tube and since the novel features of the present application are not dependent upon the use of the mechanism in pairs, I have deemed it unnecessary to illustrate a whole machine but have illustrated only those features necessary to clearly disclose what is new in the present case.

The mechanism is actuated from a power shaft 12 carrying a pair of cams 13 disposed upon opposite sides of a central cam 14. The function of cams 13 is to thrust against rollers 15 that are carried by the cross head comprising yoke members 16, tie bar 17 and rods 18, to thrust these parts toward the right in Fig. 1 and against the tension of springs 19. The springs 19 bear

between a fixed frame member 20 and the flange 21 of a die carrier 22.

The die 23 has a flaring mouth 24 adapted to receive and support the projecting end 25 of the tube 26 of the explosive cartridge; the tube entering the mouth of the die as the die moves toward the tube, until the end of the tube abuts against the thimble 27. This thimble is rearwardly flared, as indicated at 28. The die and thimble are removably mounted upon the die carrier by screws 29; the die, die carrier and a sleeve 30 being mounted for reciprocation together.

A sleeve 31 adjustably mounted through the medium of a lock nut 32 in the fixed frame member 20 has its forwardly projecting portion 33 removably connected to the fixed annular cutter 34 by means of a split ring 35, said split ring being of channel formation and being adapted to engage over the collars 36 and 37 of the cutter 34 and extension 33, respectively. The rear face of the die 23 or the forward face of sleeve 30, as the case may be, or both of these elements, may be transversely channelled to provide a passage 38 for the strip of paper from which the wads are to be cut. The actual cutting is effected when the sharp rear edge 39 of the die moves over the sharp outer and forward edge of the annular cutter 34.

In Figure 1, the parts are shown in the position that they occupy after the cutting of the paper has been effected by the rearward movement of the die with respect to the annular cutter; the die having moved rearwardly past the forward cutting edge of the cutter and the severed piece of paper from which the wad is to be formed, being indicated at 40. In the rearward movement of the die under the influence of the cams 13, the rear edge of the thimble is brought close enough to the forward end of the cutter 34 to hold the paper disk 40 in position but not close enough to tightly bind said paper disk 40.

It is important to note that the cutting action takes place when the die is moving away from the explosive package. This makes for safety in that it minimizes the possibility of any particles of explosive being in a position to be set off during the cutting action.

A forming plunger head 41 is mounted within the cutter 34 and is actuated by a tubular rod 42 under the influence of cam 14. After the paper has been cut off by the action of cams 13, the springs 19 act to yieldingly thrust the die 23 toward the tubes or cartridges 26 to thereby cause the free ends of said tubes to enter the die to be supported by the same while the wads are being thrust into said tubes. At the same time that the die starts to move forwardly or toward the tube, the plunger 41 moves forwardly and the cams 13 and 14 are so shaped and arranged that the plunger moves somewhat faster than the die so that by the time the tubes are positioned and seated in the mouths of the dies, and said dies have come to rest, the plunger will have thrust the paper disk 40 forwardly in such manner as to cause the flared portion 28 of the thimble to cup the edge of the disk and to bring said disk into position to immediately enter the mouth or open end of the tube 26. It is also important to note that the flanged wad is moving forward through the drawing throat, as the shell or tube is positioned and seated in the mouth of the die. This assures against any loose particles of explosive, which may fall out at this point, dropping into the cutting and forming portions of the die. Any loose particles which may fall out

of the shell will be pushed back toward the cartridge by the advancing wad.

It will be observed that the rearward or cutting action of the die is a positive one under the action of cams 13, while the forward movement of the die is a cushioned one under the action of springs 19. Conversely, the action of the plunger 41 forwardly is a positive one under the movement of the cam 14, while the rearward movement of the plunger is a cushioned one under the action of a spring 43 which surrounds the rod 42 and bears between a shoulder of sleeve 31 and a washer 44 disposed in front of a forked element 45 which carries a roller 46 against which the cam 14 thrusts. A lock nut 45a binds the forked element upon tubular rod 42.

The wad forming and placing mechanism of the present invention differs from that of my prior application in that I recess the forward end of the plunger 41, as indicated at 41a, and mount within said recessed portion an auxiliary plunger head 41b that is mounted upon a rod 41c. This rod passes through the tubular rod 42 and at its rear end (see Figure 4) is connected to a head 41d. Head 41d carries rearwardly projecting wings 41e adapted to be engaged by pins 14a on cam 14. The movement of head 41d toward the rear is under the influence of a spring 41f which bears between said head and a plate 41g that is clamped in position by lock nut 45a.

The function of the plunger 41 is to cup the cut-off paper disk by thrusting it forwardly into the contracting throat of the thimble. However, this plunger does not actually move into the open end of the paper tube 26. It moves only to a point at about the forward or left hand edge (in Figure 1) of the thimble. The actual work of advancing the wad from that point and seating it in the open end of the tube 26 is done by the auxiliary plunger 41b under the influence of the pins 14a on cam 14.

Where the work of cupping the paper wad and the seating it in the open end of tube 26 had to be done entirely by plunger 41, as in my aforesaid application, it was necessary to guard against the ends of the paper tubes being deformed or out of truly circular formation. This was due to the fact that it was necessary to make the plunger 41 very nearly as large in diameter as the internal diameter of the paper tube and consequently the plunger could not enter the end of the tube if the tube was very much out of round. The arrangement described herein very completely obviates that difficulty by effecting the cupping of the material by an element large enough for that purpose while seating the cupped material through the medium of an element so much smaller in diameter than the internal diameter of the paper tube that it makes no difference whether the paper tube happens to be exactly circular or not.

As the smaller plunger 41b advances the wad, the edges of the latter yield and pass by any kinks or irregularities in the end of the paper shell, and after entering the shell the wads resume their normal shape and are properly seated.

I find that this arrangement saves delays which might otherwise be occasioned and renders unnecessary the use of separate tube truing means, such as that shown for example at 50 and 70 in my former application.

The movement of the die in its cutting off action or in its movement toward the right in Figure 1 is a positive movement under the influence of cams 13, as before stated, while the

return movement of the die, i. e., its movement which brings it into seating relation upon the end of the paper tube, is a cushioned movement under the influence of the springs 19. In order 5 to insure that there will be no sticking of the parts and failure to operate under the influence of springs 19, I have mounted upon the inner face of the yokes 16, kick plates 16a adapted to be engaged by pins 13a upon the cams 13; said 10 pins serving to impart an initial forward kick to the die to carry it clear of the annular cutter 30; the movement of the die into engagement with the paper tube 26 being then completed and being a cushioned one under the influence 15 of the springs 19.

To prevent any undesirable pumping or suction action, incident to the movement of auxiliary plunger 41b in the recessed end 41a of plunger 41, I have vented said recess, as indicated at 41h; the sides of the plunger 41 being channeled or otherwise relieved, as indicated at 41'. To aid in preventing powder dust from being forced back into the mechanism as the plunger 41 moves forwardly, I have transversely 25 vented the die and thimble, as indicated at 23a. Since the die moves into engagement with the paper tube before the plungers 41 and 41b complete their movements, it follows that there would be no escape for any powder dust which happened to be within the mouth of the die or adjacent thereto. If the vents 23a or their equivalents were not provided, the action of the plungers might result in forcing some of this powder dust back into the mechanism with 30 consequent increased hazard, and it is to guard against this possibility that I vent the die and thimble, as illustrated in Figure 2. It will be noted that the forming end of plunger 41 is slightly spaced from the fixed annular cutter 34 35 as clearly appears in Figs. 1 and 5. The provision of this peripheral space about the plunger 41 renders it possible for the two plungers 41 and 41b to vent during the initial forward movement of said plungers. In other words, in the initial 40 forward movement of these plungers, the air, in advance of them and rearwardly of the cut wad 40, will be forced through the space 41' about the circumference of the plunger 41, and this rush of air keeps these surfaces clean and free 45 of any powder particles. Further, it will be seen that as soon as the paper groove 38 (see Fig. 5), in its movement toward the cartridge, passes the forward or cutting end of the fixed cutter 34, the 50 space between the rear of plunger 41 and cutter 34 will likewise be vented through the channel or space 41', the air passing through said channel and around the cutting edge of the fixed annular cutter to said paper groove. Here, again, the rush of air through the peripheral space 55 about plunger 41 blows out any powder particles which tend to cake on the parts or to work their way back into the oil bearing surfaces.

Like the former application, the structure described lends itself to the ready substitution of other sizes of die, forming plunger, and cutter; there being no change with respect to this feature of the invention.

It is to be understood that the invention is not 70 limited to the particular arrangement shown but that any equivalent structure for accomplishing the same results, falling within either the terms or the spirit of the appended claims, is within 75 the purview of the invention.

Having described my invention, what I claim is:

1. A device of the character described comprising a die having a mouth shaped to receive and support the end of a paper tube, of wad forming mechanism associated therewith, and means for venting the die in advance of said mechanism to permit the escape of air and powder particles during the movement of the wad forming mechanism. 10

2. A device of the character described comprising a member having a mouth shaped to receive and support the end of a tube to be capped, a wad handling plunger operable therein, and means for venting said member in advance of 15 said wad handling plunger for the purposes set forth.

3. A device of the character described comprising an element shaped to receive the end of a tube to be capped, a wad forming plunger and 20 a wad handling plunger movable within said element, and means for venting said element in advance of said plungers for the purposes set forth.

4. A device of the character described comprising a die having a mouth shaped to receive 25 and support the end of a paper tube, a removable thimble having a rearwardly flaring throat mounted in said die, a plunger cooperating with said thimble to cup a piece of material, and means for venting the thimble and die to permit 30 the escape of air from the space within the die, and in advance of the wad-handling mechanism.

5. A device of the character described comprising a die, an annular cutter with which the die co-acts, positive mechanical means for moving the die in one direction, spring means for actuating the die in the other direction, and means for mechanically imparting a positive thrust to the parts at the beginning of the spring 35 actuated movement. 40

6. A device of the character described comprising a fixed annular cutter, a die having a mouth shaped to receive the end of a paper tube, and comprising a portion co-acting with the fixed annular cutter to cut off a piece of material to 45 form a wad, a rotative cam, members engaged with the die and against which said cam acts to move the die in one direction, spring means for moving the die in the other direction, and means carried by said cam, for imparting a positive 50 thrust to the die at the beginning only, of its spring actuated stroke.

7. A device of the character described comprising a fixed annular cutter, a reciprocatory die having a throat adapted to receive the open 55 ends of tubes to be capped, spring means for thrusting the die toward the tubes, cam means for moving the die against the action of said springs, and means for imparting a positive thrust to the die actuating parts at the beginning only of the 60 spring actuated portion of its movement.

8. A device of the character described comprising a die having a mouth shaped to receive the open ends of tubes to be capped, a cutter with respect to which said die reciprocates, cams for 65 moving the die in its cutting action, spring means for moving the die in its non-cutting action and into engagement with the paper tubes, means for imparting an initial positive movement to the die in its last named movement, a forming 70 plunger movable in the cutter, a cam for moving the forming plunger in one direction and a spring for moving the forming plunger in the other direction, a second plunger of smaller diameter than the first named plunger and mov- 75

- able therein and acting to place the formed wad, spring means for retracting the last named plunger, and cam means for advancing the last named plunger.
5. 9. A device of the character described comprising a die having a mouth adapted to receive the open ends of tubes, a wad forming and placing mechanism movable within the die and comprising a cutter, a forming plunger and a placing plunger movable within the forming plunger, a tubular rod by which the forming plunger is carried, a rotative cam thrusting against and acting upon the rear portion of said tubular rod to advance the same, a rod upon which the placing plunger is mounted and passing through the tubular rod, cam plates carried by the rear end of the last named rod, and members carried by the rotative cam and acting upon said cam plates to advance the placing plunger.
10. 10. A device of the character described, comprising a die, a cutter co-acting with said die, a forming plunger movable in the cutter, a placing plunger movable axially in the forming plunger, a tubular rod by which the forming plunger is carried, a rod by which the placing plunger is carried, a bifurcated member upon the rear end of the tubular rod, a part carried by said bifurcated member and spanning the space between the arms of the same, a cam, the periphery of which bears upon said part, spring means tending to hold the tubular rod against the periphery of the cam, a head carried by the rod of the placing plunger, which head lies between the sides of the bifurcated member, and the upper portion 35 of which projects beyond said bifurcated member, spring means tending to thrust the said head rearwardly with respect to the bifurcated member, pins projected from the opposite sides of the cam, and wings lying in the path of movement 40 of said pins, and connected to the said head.
11. In combination a die, an annular cutter co-acting with said die, a first plunger movable in the cutter and initially cupping the material to form wads, and a second plunger movable 45 through the first named plunger, and placing the wads so formed.
12. A device of the character described comprising a die, a cutter co-acting with said die to sever pieces of cap material, a forming plunger 50 movable in the cutter to cup the material cut off by the cutter, and a second plunger movable through the first named plunger for placing the cupped material.
13. A device of the character described comprising a die, a fixed annular cutter, means for reciprocating the die with respect to the cutter to thereby cut off a piece of wad forming material, wad forming and placing mechanisms movable through the die to form and place a wad 55 of the material cut off, said die being vented at a point in advance of the formed wad to permit the escape of air from the space within the die and ahead of the formed wad, as set forth.
14. A device of the character described comprising a die, a fixed annular cutter, means for reciprocating the die with respect to the cutter to thereby cut off a piece of wad forming material, wad forming and placing mechanisms movable through the die to form and place a wad 60 of the material cut off, said die being vented at a point in advance of the formed wad to permit the escape of air from the space defined cir-
- cumferentially by the die, rearwardly by the cut wad, and forwardly by the element which receives the wad.
15. In a device of the character described, a die, a first member comprising an annular cutter, a second member for forming wads and located within said first member, a third member for placing the formed wads and located within said second member, at least a portion of said second member being movable outwardly beyond the cutting edge of said first member and into the die, at least a portion of said third member being movable outwardly from the interior of the second member and through the die, and a vent for the space between the second and third members, said vent communicating with a channel arranged between the first and second members.
16. A machine for capping the ends of explosive containing tubular receptacles, comprising a die, an annular cutter, a forming plunger located within the annular cutter and movable with respect to said cutter, said forming plunger being spaced from said annular cutter to a degree sufficient to permit air flow between said plunger and cutter and about the periphery of the plunger to thereby prevent stray powder particles from caking between said cutter and plunger.
17. A machine for capping ends of explosive containing receptacles comprising a die, an annular cutter, a forming plunger located within the annular cutter and movable with respect to said cutter, the forming end of said plunger being slightly spaced from said annular cutter and the remainder of said plunger being further spaced from said annular cutter to thereby permit the ready passage of air past said plunger to prevent the accumulation of stray powder particles between said cutter and plunger.
18. In a device of the character described, a die, a first member comprising an annular cutter, a second member comprising a wad forming plunger located within said first member, at least a portion of said plunger being movable outwardly beyond the cutting edge of the annular cutter and into the die, and means for venting the space between the first member and the second member which includes an air passage peripherally about the plunger substantially throughout the length thereof.
19. A machine for capping the ends of explosive containing receptacles comprising a die dimensioned to receive and form a substantially snug fit upon the open ends of paper tubes of explosive, to be capped, an annular cutter, means for feeding a strip of wad forming material across said annular cutter, said die cooperating with said cutter to cut said wad forming strips, means carried by the die for pressing said cap about its edge against the forward end of the annular cutter, a forming plunger mounted for longitudinal movement in the annular cutter, a placing plunger movable in the forming plunger and means for venting the space between said plungers and the formed cap peripherally about the forming plunger, the passage of air about the periphery of said plunger keeping the space between the forming plunger and the annular cutter clean and free of the accumulation of powder particles.
